(57) **CLAIM**

The ornamental design for a “drinking container cap assembly,” as shown and described.

DESCRIPTION

FIG. 1 is a top, front, and right side perspective view showing my new design for a drinking container cap assembly and with the cap closure in a closed configuration.

FIG. 2 is a top view of the drinking container cap assembly shown in FIG. 1.

FIG. 3 is a right side view of the drinking container cap assembly shown in FIG. 1, the left side being a mirror image thereof.

FIG. 4 is a front view of the drinking container cap assembly shown in FIG. 1.

FIG. 5 is a rear view of the drinking container cap assembly shown in FIG. 1.

FIG. 6 is a bottom view of the drinking container cap assembly shown in FIG. 1.

FIG. 7 is a top, rear, and left side perspective view of the drinking container cap assembly shown in FIG. 1, but with the cap closure in an opened configuration.

FIG. 8 is a top view of the drinking container cap assembly shown in FIG. 7.

FIG. 9 is a left side view of the drinking container cap assembly shown in FIG. 7.

FIG. 10 is a front view of the drinking container cap assembly shown in FIG. 7.

FIG. 11 is a rear view of the drinking container cap assembly shown in FIG. 7; and,

FIG. 12 is a bottom view of the drinking container cap assembly shown in FIG. 7.

The dashed lines are for illustrative purposes only and form no part of my claimed design.
